(57) **CLAIM**

The ornamental design for a cooking utensil, as shown and described.

DESCRIPTION

FIG. 1 is a top, front perspective view of a cooking utensil showing my new design;

FIG. 2 is a front view thereof;

FIG. 3 is a rear view thereof;

FIG. 4 is a side view thereof;

FIG. 5 is an opposite side view thereof;

FIG. 6 is a bottom view thereof; and,

FIG. 7 is a top view thereof.

The broken lines in the drawings illustrate environmental structure and form no part of the design.
